DESIGN FOR A CHAIR

Frederick T. Paden, Collingswood, N. J.

Application March 1, 1949, Serial No. 1,158

Term of patent 7 years

(Cl. D15—1)

To all whom it may concern:

Be it known that I, Frederick T. Paden, a citizen of the United States of America, residing at Collingswood, in the county of Camden and State of New Jersey, have invented a new, original, and ornamental Design for a Chair, of which the following is a specification, reference being had to the accompanying drawings, forming a part thereof.

Figure 1 is a perspective view of a chair, showing my new design;

Figure 2 is a rear elevational view thereof; and Figure 3 is a side elevational view.

I claim:

The ornamental design for a chair, as shown.

FREDERICK T. PADEN.
